Harry A. Douglas
By J. L. Bragg
Atty.

UNITED STATES PATENT OFFICE.

HARRY A. DOUGLAS, OF BRONSON, MICHIGAN.

FOCUSING LAMP.

Original application filed January 26, 1920, Serial No. 354,306. Divided and this application filed May 23, 1921. Serial No. 471,950.

To all whom it may concern:

Be it known that I, HARRY A. DOUGLAS, a citizen of the United States, residing at Bronson, in the county of Branch and State of Michigan, have invented a certain new and useful Improvement in Focusing Lamps, of which the following is a full, clear, concise, and exact description.

My invention relates to focusing lamps, 10 being a division of my application Serial No. 354,306, filed January 26, 1920.

The invention is of particular service in relation to electric headlights employed, for example, upon automobiles. In such a lamp 15 there is a reflector including a reflector containing casing, a tubular holder upon and within the casing, a shell within the holder, an incandescent lamp bulb within the shell, the holder being formed with a spring 20 tongue gripping the shell and also being formed with a projection apart from the tongue while the shell is formed with a longitudinal slot receiving said projection.

In accordance with another characteristic 25 of the invention there is an adjusting rod in novel assembly with the lamp holding shell.

I will explain my invention more fully by reference to the accompanying drawing showing the preferred embodiment thereof 30 and in which Fig. 1 is a view partially in section and partially in elevation of a portion of an automobile headlight structure made in accordance with the invention; Fig. 2 is a view of parts shown in Fig. 1 taken 35 at right angles thereto, the casing and reflector portions alone being shown in section; Fig. 3 is a view in elevation of certain of the parts shown in Fig. 1 looking from beneath these parts as they appear in the latter figure; Fig. 4 is a view showing, in section, the preferred form of casing prior to its assembly with the threaded adjusting sleeve which is shown in elevation in this figure; and Fig. 5 illustrates, by the full lines 40 thereof, the threaded adjusting sleeve inserted as far within the casing as possible before the casing is modified to complete its assembly with such sleeve, the assembled positions of these parts being indicated by 45 dotted lines.

Like parts are indicated by similar characters of reference throughout the different figures.

The concave reflector 1 is received in the

concave casing 2 and is coupled therewith in 55 any suitable way, space intervening between the reflector and casing. The reflector includes a forwardly extending tubular continuation or sleeve 3 in fixed relation with the balance of the reflector and supported by 60 the casing since the reflector that holds the sleeve 3 is supported by said casing. This continuation 3 constitutes a holder or mounting that is in the form of a tubular neck. The shell or tubular element 4 is contained 65 within the bore of the sleeve 3 and when these two elements are embodied in a headlight structure the shell is made to be adjustable longitudinally of the sleeve. One of the elements 3 or 4, preferably the sleeve, 70 is formed with circumferentially aligned spring tongues 5 which press transversely of and upon the shell. These spring tongues are desirably produced by means of a T-slot whose stem portion 6 extends longitudinally 75 of the sleeve and whose head portion 7 extends circumferentially of the sleeve, the slot portion 6 extending clear to one end of the sleeve in order that the springs may be completely formed to have the desired degree of flexibility. The shell 4 has a recess 8 formed therein, this being the case if the sleeve is formed with the springs 5, it being understood that the invention is not to be limited to the formation of the springs upon 80 the sleeve and the recess in the shell. The element which has the springs, in this instance the sleeve, has a projection 9 apart from the spring which enters the recess 8. The shell has bayonet channels 10 for receiving the bayonet projections 11 upon a contact carrier 12. As illustrated, this contact carrier is in the form of a base of a so-called single pole incandescent lamp bulb 13 whose filament has one terminal in connection with a contact 14 upon the inner end of such base and whose other terminal is connected with a metallic sheath upon the base which electrically engages the metal shell 4 that, in turn, is in electrical connection with the sleeve 3 that is in suitable "grounded" connection with one terminal of the source of current that is employed for supplying the lamp bulb.

When the device is employed in a headlight such as is employed in automobiles, the shell 4 is made free to be adjustable back and forth within the sleeve 3 by making the re-

cess 8 longer than the projection 9 and extending this recess longitudinally of the shell.

In assembling the sleeve 4 within the shell 3 the sleeve is inserted within the shell and is pressed transversely of the sleeve sufficiently to permit the projection 9 to ride over the shell and come into the recess, the springs 5 yielding in this process and there-
10 after contracting into tight engagement with the shell to maintain the projection within the recess and to frictionally hold the shell in longitudinal adjustment within the sleeve.

The sleeve also has a contact carrier 15 held in assembly with the shell as set forth and claimed in my companion application Serial No. 348,416, filed December 30, 1920. This contact carrier supports a metallic spring barrel 16 in which there is housed 20 a coil spring 17 that presses a contact 18 into engagement with the lamp bulb contact 14. This spring barrel has an external continuation 19 formed with a lateral opening 20 that may receive a plug 21, the spring 17 pressing a rear contact 22 into engagement with this plug as set forth in my aforesaid co-pending application. Current is conveyed to the lamp by means of the plug 21, the contacts 18 and 22, and the spring barrel 30 16 electrically connecting these contacts.

The rod 23 is coupled with the shell 4 for the purpose of moving this shell to adjust the focal position of the lamp bulb. This rod is preferably assembled with the shell by means of the construction illustrated, the shell having an aperture 24 in the rear portion of its cylindrical wall which receives a transverse continuation 25 of the rod 23. To prevent the rod from being withdrawn laterally from the shell it is provided with a longitudinal portion 26 extending forwardly from the transverse continuation 25 of the rod. In assembling the rod and shell the rod is first placed at an angle to the shell to permit of the passage of the longitudinal portion 26 into the aperture 24 whereafter the rod is turned to be longitudinal of the shell and to bring the transverse continuation 25 50 into said aperture.

In carrying out another feature of the invention the rod is threaded about its rear end and is in threaded engagement with the threaded bore of an adjusting sleeve 27. 55 This sleeve is given a single plane of rotation by being provided with an annular groove 28 into which is extended the portion of the casing 2 that surrounds the opening in

the rear of this casing through which the adjusting sleeve 27 is passed. For convenience in turning the sleeve 27 the outer and head end of this sleeve is formed with a screw-driver slot. The annular groove 28 in the adjusting sleeve 27 enables me to dispense with an added part which was hitherto employed for confining such a sleeve to a single plane of rotation. In the process of assembly the rear portion of the casing 2 is initially of the shape illustrated in Fig. 4 where it is shown as being provided with a rearwardly extending truncated conical portion 29 surrounding the opening in this casing with which the adjusting sleeve is to be assembled. The inner edge of the truncated conical portion 29 is first brought into registry with the annular groove 28 as illustrated in Fig. 5, whereafter said conical portion 29 is flattened to bring it into the general curvature of the casing 2 and to cause it to enter the groove 28, as illustrated in Figs. 1 and 2.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

In a focusing lamp structure, a reflector, a lamp carrying sleeve mounted for forward and backward movements with respect to said reflector whereby focal adjustments of the lamp may be effected; and means for imparting forward and backward movements to said sleeve including a rod connected at its forward end to said sleeve and extending rearwardly therefrom, said rod having a substantially right angularly extending portion engaged in an opening in said sleeve and further having a longitudinal portion extending forwardly from said right angular portion and engaging the inner face of the sleeve whereby the rod is held positively against disengagement from the sleeve when the rod is in a rearwardly disposed position with respect to the sleeve and whereby the rod is readily disengageable from the sleeve by swinging the rod to align the aforesaid forwardly extending longitudinal portion with the opening in said sleeve.

In witness whereof, I hereunto subscribe my name this 28th day of June A. D., 1920.

HARRY A. DOUGLAS.
